CLAIM

The ornamental design for a device with rotatable top for training proper foot placement and movement for batters, as shown and described.

DESCRIPTION

FIG. 1 is a perspective view of a device with rotatable top for training proper foot placement and movement for batters, embodying the design of the present invention;
FIG. 2 is a front elevational view thereof;
FIG. 3 is a rear elevational view thereof;
FIG. 4 is a left side elevational view thereof, the right side elevational view being a mirror image thereof;
FIG. 5 is a top plan view thereof;
FIG. 6 is a bottom plan view thereof; and,
FIG. 7 is a perspective view showing the device with rotatable top for training proper foot placement and movement for batters in use; the broken line showing of environmental structure is for illustrative purposes only and forms no part of the claimed design.
